ATT'YS.

UNITED STATES PATENT OFFICE.

THOMAS J. TOPPER, OF SAN FRANCISCO, CALIFORNIA.

DESIGN FOR A COFFEE-URN.

59,135.

Specification for Design. Patented Sept. 20, 1921.

Application filed April 14, 1921. Serial No. 461,423. Term of patent 14 years.

To all whom it may concern:

Be it known that I, THOMAS J. TOPPER, a citizen of the United States, residing at San Francisco, in the county of San Francisco and State of California, have invented a new, original, and ornamental Design for Coffee-Urns, of which the following is a specification, reference being had to the accompanying drawing, forming part thereof.

The figure is a front elevation of the coffee urn, showing my new design.

I claim:

The ornamental design for a coffee urn, as shown.

April 5th, 1921.

THOMAS J. TOPPER.
